UNITED STATES PATENT OFFICE.

WILLIAM D. WHEAT, OF JAMESTOWN, KENTUCKY, ASSIGNOR OF ONE-HALF TO ELMER WHEAT,
OF JAMESTOWN, KENTUCKY.

HARVESTER-CUTTER.

No. 872,980.

Specification of Letters Patent.

Patented Dec. 3, 1907.

Application filed February 1, 1907. Serial No. 355,307.

To all whom it may concern:

Be it known that I, WILLIAM D. WHEAT, citizen of the United States, residing at Jamestown, in the county of Russell and 5 State of Kentucky, have invented certain new and useful Improvements in Harvester-Cutters, of which the following is a specification.

This invention contemplates certain new 10 and useful improvements in cutter bars for mowing machines or reapers and the invention has for its object an improved construction of cutter bar, the parts of which are so arranged that any of the sections or teeth 15 may be removed, so that an injured or worn tooth may be taken out and ground or replaced by a new one, and a further object of the invention is to provide an improved construction of cutter bar of which the teeth or 20 sections are interlocked when in operative position, each tooth of the series locking the one next to it in place, all as will be herein-after specifically described and particularly pointed out in the appended claims.

25 For a full understanding of the invention and the merits thereof and also to acquire a knowledge of the details of construction of the means for effecting the result, reference is to be had to the following description and 30 accompanying drawings, in which:

Figure 1 is a perspective view of a cutter bar embodying features of my invention, parts being broken away; Fig. 2 is a top plan view of the cutter bar with the covering 35 strip removed; and Fig. 3 is a detail perspective view on an enlarged scale of one end of the supporting beam.

Corresponding and like parts are referred to in the following description and indicated 40 in all the views of the drawings by the same reference characters.

Referring to the drawing, the numeral 1 designates the supporting beam which is provided on one face with a series of forwardly 45 opening recesses 2 which are provided with side walls 3 oblique to lines perpendicular to the beam, the walls of one recess being separated from the walls of the next adjacent recess by means of obliquely extending lugs 4. 50 Each tooth in the series of teeth, except the last, is provided with an offset extension 5,

the side walls of which are oblique to the general plane or direction of the teeth to correspond with the side walls of the recesses and each offset 5 forms with the main portion of 55 the tooth of which it is a part, a rearwardly facing shoulder 6 and an opposite forwardly facing shoulder 7. It will thus be seen that as one tooth after another is placed within the recesses 2 in the line or series, the rear- 60 wardly facing shoulder 6 of one tooth will project over the forwardly extending shoulder 7 of the next preceding tooth. By this means, all of the teeth of the cutter bar are locked together, and to secure said teeth in 65 place and insure that this interlocking connection should be effective, I provide a locking strip 8 which extends over the offsets of all the teeth and is riveted or otherwise secured to the supporting beam 1. The last 70 tooth at the inner end of the series is provided with a shoulder 6^a corresponding to the shoulders 6 of the other teeth, but is not provided with any forwardly facing shoulder, such as the shoulders 7. This last tooth is 75 formed with a screw hole into which a screw 9 fits, said screw 9 working through the locking strip 8 and into the said tooth. Or the last tooth may be secured in place by any desired fastening means. 80

From the foregoing description in connection with the accompanying drawing, it is evident that all of the teeth are interlocked, and that in order to remove any one tooth, it is only necessary to unscrew the end tooth, 85 whereupon the other teeth may be taken out one after the other, and the worn tooth thus reground or replaced by a new one.

It will be seen that the construction is very durable and very efficient for the purposes herein set forth. 90

Having thus described the invention, what is claimed as new is:

A cutter bar consisting of a supporting beam provided with forwardly opening recesses disposed obliquely to lines perpendicular to the beam, a locking strip secured to said beam and adapted to cover said recesses, teeth provided with offset extensions, the side walls of which are disposed obliquely to the direction in which said teeth point, said extensions fitting into said re- 95 100

cesses, each of said teeth except one being provided with a rearwardly facing shoulder, and an opposite forwardly facing shoulder, and the rearwardly facing shoulder of one tooth overlapping the forwardly facing shoulder of the next tooth, the said excepted tooth being provided with a rearwardly facing shoulder overlapping the forwardly fac-

ing shoulder of the next tooth, and means for securing this last named tooth in place. 10

In testimony whereof I affix my signature in presence of two witnesses.

WILLIAM D. WHEAT. [L. s.]
